UNITED STATES PATENT OFFICE

ALEXANDER ERWIN WECK, OF DOLAU, GERMANY

MECHANICALLY-OPERATED GRATE-FEEDING MEANS

Application filed May 5, 1927, Serial No. 189,092, and in Germany December 15, 1926.

This invention has reference to mechanically operated grate feeding means provided with coal throwing shovels disposed in the stoking neck or stoking aperture of the furnace, and among other objects it is intended to facilitate the manipulation of devices of this kind and to arrive at a more thorough and more economical utilization of the furnace space. In the grate feeding devices with 10 rocking coal throwing shovels the latter are generally disposed above the stoking neck or stoking aperture, that is to say a stoking opening is provided above which there is another opening for the feeding shovel adapted 15 to distribute the coal over the grate. With the different kinds of boilers however, there is generally not sufficient height to allow of a sufficiently high stoking neck to be annexed and combined with the feeding opening for 20 the coal above the stoking neck. In such cases it has been suggested to disposed the feeding shovel within the opening of the stoking neck, so as to be able to combine a sufficiently high stoking neck with a surface of 25 comparatively low height. In the furnace spaces of this kind there will also be an additional free space for the throwing of the coal in the upward direction. Structures in accordance with these principles have how- 30 ever not been generally accepted in the arts on account of the generally unsatisfactory arrangement of the means for the actuation of the feeding shovel. Now, this invention is intended to devise new and highly satisfac- 35 tory means for the operation of the feeding shovel, which will satisfy all requirements of practical operation. The shovel in accordance with this invention is rocked in the usual manner by a suitable driving mechanism for 40 the grate feeding means. The coal itself is placed in front of the feeding shovel in the otherwise well known manner by coal admitting means. As long as the feeding shovel is rockingly reciprocated and as long as a supply of coal is dropped in front of the shovel 45 previous to each throw, the grate feeding means operate in the usual manner. If it is desired however to reach the fire space through the stoking neck, it is not sufficient 50 to arrest the grate feeding means, but it is

necessary to swing the throwing shovel upwards, so to expose the stoking neck.

This object is carried out by means and mechanism of applicant's invention which is more particularly described and pointed out 55 in the accompanying drawings, in which:

Figure 1 is a vertical cross-section on the line I—I of Fig. 2.

Fig. 2 shows a front elevation of the device with parts thereof broken away.

Fig. 3 is a side view partially in section of the device taken on line III—III of Fig. 2.

Fig. 4 is a longitudinal section of a ship's boiler with a smoke stack in front thereof and applicant's device attached thereto.

Figs. 5 and 6 are two views of the throwing shovel taken at right angles to each other.

Figs. 7 and 8 are two views of the detachable clutch coupling taken at right angles to each other.

Figs. 9 and 10 are two views of the throwing spring lever taken at right angles to each other.

Figs. 11 and 12 are two views of the hand operator for the device taken at right angles 75 to each other.

Figs. 13 and 14 are two views of the hand shifting lever taken at right angles to each other.

Figs. 15 and 16 are two views of a coupling 80 shifting lever taken at right angles to each other.

Fig. 17 is a view of a clutch operator.

Fig. 18 is a view of this clutch operator 85 fixed on its operating rod.

Figs. 19 and 20 are views of the guiding member taken at right angles to each other.

Figs. 21 and 22 are two views of an operating lug taken at right angles to each other.

The invention is a stoking device comprising the hopper A having a discharge chamber B at its lower end and an oscillating element C and guides D adapted to move the fuel from the hopper into the throwing box or chamber E all of which are adapted to be secured to the fuel opening of a furnace. Traversing the upper portion of the throwing box or chamber is the shaft b to which is secured an oscillating shovel k which takes 95 100

the movement of the shaft, which movement is derived from two sources of power to be more particularly described hereinafter. As a means for guiding the fuel to a position in front of the shovel there is provided a guide *g* in the throwing box mounted on the shaft *r* having bearings in the walls of the throwing box and one end of which extends beyond one of said walls. The shaft *b* extends at each end a distance beyond the throwing box, the walls of which are provided with proper bearings *e* therefor. At one end of the shaft there is provided means for rotating the shaft a partial revolution through a trip ping device *F* operated by some power source transmitted thereto by the shaft *F'* and connected thereto by the disengageable coupling *m* which is adapted to be engaged and disengaged by the operator *n³* secured to the reciprocating rod *n¹*. This operator can be adjusted on the rod *n²* by the nuts *n* (see Fig. 18). The other end of the shaft *b* is provided with the relatively movable collar *c¹* having the arm *c* to which are secured corresponding ends of a pair of springs *c³* the other ends of which are held by the bracket *I* secured to the device. The collar *c¹* is provided on one side with equally spaced lugs *c²* arranged parallel with the axis of the collar with walls thereof radial thereto. As a means for making the collar *c¹* rotate with the shaft *b* a sliding collar *a* is keyed to the shaft *b*, this collar being provided on its face opposite the collar *c¹* with lugs *a¹* similar to those on the collar *c¹*, which when these lugs are moved into meshing engagement with each other movement can be imparted to the collar *c¹* from the shaft *b* or to the shaft *b* from the collar *c¹*.

The operation of the device so far described is that the fuel in the hopper *A* is by various mechanisms fed down to a position in front of the shovel *k* (see Figs. 1 and 4), then rotation of the shaft *b* moves the shovel *k* backwards from this position a partial revolution of the shaft *b* through the power translating means. At the end of such partial movement the trip means *F* in the power translating means is released and the shovel *k* is moved in the opposite direction by the energy of the springs *c³*, thereby striking the fuel and trajecting it through the fuel opening in the furnace over the fire therein.

The ring *a* is also provided in its opposite face with lugs *a²* similar to the lugs *a¹* and with a circular groove *p* the purposes of which will be made more apparent herein after.

Rotatably mounted on the bearing *e* for the shaft *b* is a member *d* having a circular opening *d²* and having lugs *d³* corresponding to the lugs *a²* formed on the ring *a*. Stop lugs *e¹* and *d⁴* are provided on the bearing and the member *d* respectively. The member *d* is provided with an arm *d⁴* extending up-

wardly therefrom having laterally extending fingers *d⁵* and *d⁶*. The lower end of the member *d* is provided with a member *t*. The member *t* is in engagement with the cam arm *s* fixed on the protruding end of the shaft *r* and by means of which on rotation of the member *d* the shaft *r* is rotated. Mounted on the pivot *g* on the finger *d⁵* of the member *d* is a forked hand lever *f* having rollers *h* on the inside face of each of the forks adapted to engage in the slot *p* of the ring *a*.

Pivotal movement of the hand lever moves the ring *a* laterally to engage the ring with either of the members *d* or *c¹*. When engaged with *c¹* the operation of the shovel is as described above. When engaged with the member *d* the shaft *b* can be manually rotated by grasping the finger *d⁶* using it as a handle to move the shovel *k* to a horizontal position above the fuel opening in the furnace. The movement of the member *d* by the engagement of the member *t* with cam *s* rotates the guide *g* to a horizontal position (see Fig. 3). When the guide *g* and shovel *k* are in this position, by opening the door *H* the fire can be inspected through the throwing box and the operator is enabled to use the ordinary tools employed to rake and stir up the fire in the furnace.

As a means for engaging or disengaging the coupling *m* through the rod *n¹* and the operator *n⁵* there is provided the pivoted lever *n⁴* having a roller *o* at one end of the lever engaging in the groove in the ring *a*, thereby imparting movement of the ring *a* to the lever *n⁴*. Movement of the lever is imparted to reciprocate the rod *n¹* by link *n³* and the pivoted lever *n²*. By this means described above the operator of the device when he moves the ring *a* to either of its operative positions also disengages the coupling *m* so that rotation of the shaft *b* is controlled by the desire of the operator. Means is also provided for operating the feeding device *e* from the power translating device *F* by the link connections *H* (see Fig. 2).

It has to be understood that the invention in its broad aspects is not confined to the particular embodiments herein shown by way of exemplification only, but it may be modified to suit existing conditions to facilitate manipulations, and without thereby deviating from the spirit of the invention as expressed in the claims hereunto appended.

I claim:

1. In a mechanical stoker comprising a throwing box, means for supplying fuel to the box in charges, a shaft traversing said box, a throwing shovel mounted on said shaft, a lever loosely mounted in said shaft, spring operating means secured to the end of said lever, a hand operating lever mounted to pivot on the axis of the shaft, a movable member splined on said shaft, and engageable with either of said levers, and means to

move said movable member into engagement with either of said levers.

2. In a mechanical stoker comprising a throwing box, means for supplying fuel to the box in charges, a shaft traversing said box, a throwing shovel mounted in said shaft, a lever loosely mounted on said shaft, spring operating means secured to the end of said lever, a movable member splined on said shaft, interengaging means on said member and lever, a hand operating lever mounted to pivot on the axis of the shaft, the movable member being located between the hand operating lever and the lever to which the spring means are secured, adjacent faces of the hand operating lever and the movable member being provided with interengaging means, and means for moving said movable member to engage either with the spring operated lever or with the hand operating lever.

3. In a mechanical stoker comprising a throwing box, a shaft traversing the throwing box to which a throwing shovel is secured, a second shaft traversing said throwing box and to which a fuel guiding member is secured, a hand lever pivoted to rock on the axis of the shaft to which the shovel is secured, releasable means to connect the hand lever to the shaft to rotate the shaft, a cam lever on the shaft holding the guiding member, means on the hand lever adapted to engage said cam lever to rotate the shaft carrying the guiding member whereby the shovel and the guiding member are moved simultaneously to an inoperative position.

In testimony whereof I affix my signature.
ALEXANDER ERWIN WECK.
